UNITED STATES PATENT OFFICE

164,592

PAIR OF RIMLESS SPECTACLES OR SIMILAR ARTICLE

Leslie W. Myers and Albert L. Anderson, Minneapolis, Minn., assignors to Precision-Cosmet Company, Inc., Minneapolis, Minn., a corporation of Minnesota

Application December 18, 1950, Serial No. 13,482

Term of patent 14 years

(Cl. D57—1)

To all whom it may concern:

Be it known that we, Leslie W. Myers and Albert L. Anderson, both citizens of the United States, both residing at Minneapolis, Hennepin County, Minnesota, have invented at new, original, and ornamental Design for a Pair of Rimless Spectacles or Similar Article, of which the following is a specification, reference being had to the accompanying drawing, forming a part hereof.

Fig. 1 is a front elevation illustrating application of a pair of rimless spectacles or similar article, showing our new design; and

Fig. 2 is a top elevational view thereof.

The essential feature of our design for a pair of rimless spectacles or similar article resides in the parts shown in full lines.

We claim:

The ornamental design for a pair of rimless spectacles or similar article, substantially as shown and described.

LESLIE W. MYERS.
ALBERT L. ANDERSON.
